DESIGN FOR A CASING FOR A TOASTING MACHINE

Joseph Pavelka, Jr., St. Louis, Mo., assignor to
Joseph Pavelka, St. Louis, Mo.

Application October 24, 1938, Serial No. 80,646

Term of patent 7 years

To all whom it may concern:

Be it known that I, Joseph Pavelka, Jr., a citizen of the United States, residing at St. Louis, Missouri, have invented a new, original, and ornamental Design for a Casing for a Toasting Machine, of which the following is a specification, reference being had to the accompanying drawing, forming part thereof.

Figure 1 is a front perspective view of the casing for a toasting machine; and

Figure 2 is a detailed sectional view, taken on line 2—2 of Figure 1.

The end of the casing not shown is identical with the end shown and the rear of the casing is plain.

I claim:

The ornamental design for a casing for a toasting machine, substantially as shown and described.
